UNITED STATES PATENT OFFICE.

JOHN DONLEVY, OF NEW YORK, N. Y.

FORMING PLATES FOR POLYCHROMATIC PRINTING.

Specification of Letters Patent No. 10,363, dated January 3, 1854.

To all whom it may concern:

Be it known that I, JOHN DONLEVY, of the city, county, and State of New York, have invented a process or method of producing intagliographic, illuminated, and polychromatic printing-plates, door-plates, window-plates, number and dial plates, monument and inscription plates, and other such like plates, which process or method I 5 nominate "chromo-glyphotype," of which the following is a full, clear, and exact description, reference being had to the accompanying drawings, making part of this specification, in which—

15 Figure 1, represents types of intagliographic letters such as are used by printers and called open or outline letters; Fig. 2, a perspective view of a chase and galley in which the form of types is to be set up; Fig. 20 3, a perspective view of a tablet of glass in a frame; Fig. 4, a cross section of the form of types, chase, galley and tablet clamped together; Fig. 5, the intagliographic printing plate produced in accordance with the 25 first part of my invention; Fig. 6, types or blocks representing elements of forms which can be arranged and combined to produce designs as represented in Fig. 7; Fig. 8, embossed letters; Fig. 9, illuminated or shaded 30 letters; Fig. 10, shaded intagliographic types; Fig. 11, polychromatic letters; Fig. 12, stencil plate used in the process for obtaining polychromatic printing plates.

The same letters indicate like parts in all 35 the figures.

The first part of my invention relates to the method of producing intagliographic printing and other plates, that is, plates in which the subject is sunk beneath the general surface of the plate which represents the ground, so that for printing plates they shall produce, in printing therefrom, that intagli-chromo-graphic effect heretofore and now generally produced by the expensive processes of xylography and chromolithography; and for door plates, tablets, &c., the same effect and appearance as that heretofore and now generally produced by the expensive processes of engraving and die sinking. And this part of my invention 40 consists in setting up the subject in intagli types generally used by printers and called "open or outline letters" and after locking up the matter in a chase or its equivalent 45 and securing them on a galley or bed, cast-

50 ing plaster of Paris or other equivalent substance or composition around the letters while the surface of the letters are held in close contact with a plate of glass or the equivalent thereof, so that the plaster or its 55 equivalent shall fill up the entire surface around the letters to a plane with the surface of the types except the intagli letters, characters or figures and then stereotyping the subject thus set up and prepared, by 60 means of which method I am enabled to 65 present a plate with the subject in exact duplicate of the intagli letters, characters or figures, and with the remaining surface 70 of the plate on the same plane with the outline of the types, as if the same had been 75 engraved, but with the important advantage of having all the characters of equal depth and with the bottom as smooth and even as the types from which the plate is 80 produced. And this part of my invention 85 applies equally to the production of such plates from a form of types representing ornamental or other delineations as from letters or characters, and whether the plates 90 be cast of stereotype or other metal or composition.

The second part of my invention relates to the method of making plates for embossing and to be employed in connection with 95 intagliographic plates produced in accordance with the first part of my invention. And this part of my invention consists in taking a cast in plaster or its equivalent, from a plate produced in accordance with 100 the first part of my invention, and then stereotyping such cast, that is to say, taking a second plaster cast from the first plaster cast and then a metal cast from the second plaster cast, which metal plate will be a reverse duplicate in relief of the intagliographic plate and fitting therein, so that in taking impressions on paper or other substance, the intagliographic plate is used to print the letters, &c., in intagli on one surface and then the impression is made on the other side of the paper, &c., which forces up the intagli letters, &c., producing that effect called embossing.

The third part of my invention relates to 105 the method of producing illuminated printing plates, that is plates for printing shaded intagliographic letters, characters or figures, and this part of my invention consists in producing an intagliographic plate in ac- 110

cordance with the first part of my invention, from a form of shaded intagliographic types, and after such plate has been produced, removing the plaster from the form 5 of types, so that after an impression has been taken with the intagliographic plate, a second impression can be taken with the form of types or a stereotype taken therefrom to print the shades, the two impressions corresponding perfectly, the one being produced from the other. And the last part 10 of my invention relates to the production of polychromatic printing plates for printing in several colors, and consists in obtaining 15 from an intagliographic plate produced in accordance with the first part of my invention a plate or series of plates to register with the first and to print within the open letters, characters or figures produced by the first plate, which second or polychromatic plate is obtained by taking an impression in wax or its equivalent from the first or intagliographic plate which produces the duplicate in reverse and in relief, and casting 20 plaster around the relief letters or figures, and then removing whole or part of the wax from the plaster plate which may be termed a stencil plate and then finally taking a 25 plaster cast from that face of the stencil plate opposite to the face which was in contact with the wax and then stereotyping such last plaster cast whereby I am enabled to 30 produce a plate or series of plates, which, together, will correspond exactly with—being 35 an emanation from—the intagliographic plate, but with the letters, characters or figures in relief so as to print in the open letters produced by the intagliographic plates.

40 Mode of procedure for producing an intagliographic printing plate—that is, a plate, the letters or subject matter of which is sunk beneath the surface, that after the impression has been made therefrom the form of the letters or the subject matter shall be left of the original color of the paper or surface on which the impression is made: Take the usual intagliographic letters called "open or outline letters" (Fig. 1) 45 and set them up in a form in the usual manner, and lock them up in a chase *a* (Fig. 2) and then secure them on a galley *b* of wood or metal. The letters being thus arranged and secured take a tablet *c*, Fig. 3, which 50 consists of a plate of glass properly secured to a frame or block of wood *d* with flanches *e* on three sides, that project over the edges of the galley. The face of the tablet is then to be laid on the face of the types and the 55 whole secured together by means of clamps *f* so that the face of the glass tablet shall be pressed in close contact with the face of the types. The whole thus clamped together, is placed with that edge of the tablet upward 60 which has no flanch as in the section (Fig. 65

4). When thus arranged take plaster of Paris in the liquid state, as used in stereotyping, and pour it in, to fill up the entire space around the types. After the plaster has become thoroughly set, loosen the clamps 70 and remove the tablet, when it will be found that the plaster surface is on the same plane with the surface of the types leaving the intagliographic characters sunk beneath the surface of the original letters and the plaster 75 cast around them. From this take a plaster cast in the same manner as stereotypers mold a form, which cast will have the characters or subject matter in relief that is projecting from the general surface or 80 ground, and from this plaster cast take a metal cast or stereotype plate Fig. 5, in which the letters or characters will appear precisely as in the form of types first set up 85 and with the general surface on one plane 90 and the letters or characters sunk in beneath such surface, as if engraved—which plate I term an intagliographic plate. From plates thus prepared impressions can be taken in which the surface of the letters or characters will be left of the original color of the paper or other substance on which the impression is made the ink for the impression being applied to the entire surface of such plates except such portions as are sunk 95 beneath the general surface and which constitute the characters or subject-matter.

Printing from such plates will produce that intaglio-chromo-graphic effect heretofore produced by the expensive processes of 100 xylography and chromo-lithography.

Instead of letters or characters, intagliographic plates can be produced in the same manner for printing ornaments and delineations of all kinds by setting up in like manner intagliographic types of the forms required, and for this purpose I make types of what may be termed the elements of forms. Some of these are represented separately at Fig. 10, and a number of them arranged in 105 the form of a design in Fig. 7, and attached to a plate *h* instead of being secured in a chase as in the case of letters, although such types may be made with stems like other types, so that they can be secured in a chase 110 and on a galley. For securing these elements when made as represented the surface of the plate *h* or galley should be first coated with a thin layer of any suitable adhesive substance or cement, and on this draw the 115 design required to be produced and arrange the types or elements of form along these lines and press them into the adhesive coating, or these elements may be tacked onto the surface of a block, and if the figures of 120 the designs are such that the inside of the figures do not communicate with the outside, so that the plaster can run all around them, notches should be cut in from the under surface of some of the elements as shown at *i*, 130

Fig. 6, and when the design is arranged the glass tablet is to be applied and secured thereto and clamped and the plaster run in as in the first example with letters, and after 5 that a plaster cast is to be taken and from the plaster cast the intagliographic plate is produced as before described with letters. In this way, intagliographic plates can be produced with designs of any kind from 10 types or elements of forms at very little cost, from which impressions can be produced without the expensive processes heretofore practised.

Metal door plates, window plates, signs, 15 tablets, inscriptions and ornaments for monuments, tombs, &c., can be produced in the same manner and with any desired inscription ornament or design; for after the plaster cast has been taken from the form 20 of types or elements of forms properly arranged, and surrounded by plaster as above described, any kind of metal or composition can be cast in the plaster mold thus obtained to produce duplicates in intaglio 25 of the types or forms first arranged and set up, and with the entire face on the same plane with the surface of the types.

If desired the ground can be further or 30 namented in relief by previously cutting ornaments in the face of the glass tablet which is laid on the types preparatory to pouring in the plaster solution, so that the plaster ground surrounding the types of letters, characters or design, will have the 35 ornaments which were cut on the face of the tablet, in relief, while the letters, characters or design first set up in types will be in intaglio. The plaster cast taken from this will be the reverse of all this, that is, 40 with the ornaments in intaglio that were cut on the tablet, and the original matter set up in relief, and hence when the metal plate is cast therefrom it will reproduce the original.

45 Instead of the glass tablet any other substance can be substituted to which plaster will not adhere, although I prefer to use glass, and I would also remark that I do not limit myself to the use of plaster in solution to run around the form of types and for stereotyping, as other substances may be found to answer the purpose, but I mention the use of plaster as I have employed it with success. Mode of procedure 50 for making embossing printing plates, that is plates for printing the surface and raising the characters or ornamental configurations such as are represented at Fig. 8: First produce an intagliographic plate in the 55 manner above described as constituting the first part of my invention, and secure it in a chase or galley, and after properly oiling the surface take a plaster cast therefrom which will be the exact reverse thereof, fitting 60 every part of the plate on which it is

molded. Then stereotype this plaster cast, that is take a plaster cast from it which will be the same as the intaglio plate and then from this second plaster cast obtain a metal plate (Fig. 8) which will be the embossing plate, for every concavity of the first or intaglio will be in relief on this, and vice versa, the one fitting within the other in the most perfect manner. In this way by printing on one side with the intagliographic plate, and then impressing on the other side with the second or relief plate, the letters or figures will be forced up and produce the embossed effect. The advantages of this mode of procedure, are that 80 the figures or characters of the one plate will accurately fit the corresponding figures of the other plate, and as the first or intagliographic plate, is obtained from types set up in a chase and secured in a galley so 85 that the surface of all of them will be on the same plane and the concavities of the intagliographic plate are produced by molding and casting therefrom it must follow that the bottom of all the concavities of the 90 intaglio plate will be smooth and on one and the same plane so that the surface of the relief characters or figures on the embossing plate will be on the same plane and will produce good relief or raised impressions. 95

I am thus enabled to avoid not only the great expense of cutting a matrix and die plate to fit each other which is attended with great labor and expense, but at the 10 same time the surface of the two plates must be of corresponding planes which could scarcely be done by obtaining a re-duplicate from an engraved plate, for it would be very laborious and expensive, to cut the 10 bottom surface of intaglio letters or characters of an equal depth and smooth, and if not of equal depth and smoothness then the upper surface of the relief characters or figures of the embossing plate will be imperfect and unfit for use, as it will have all the imperfections of the engraving, and therefore wholly unadapted to embossing or printing relief characters or figures.

Mode of procedure for producing illuminated printing plates, that is plates for printing shaded letters, characters and figures as represented at Fig. 9: For the production of such plates first proceed precisely as above described to produce an intagliographic printing plate except that in setting up the matter what are called shaded intaglio types (see Fig. 10) should be selected, and after thus producing an intagliographic plate, saturate the plaster 11 which was cast around the types with fish oil which has the effect to separate it from the types so that it can be readily removed. And for printing, either use the types thus 11 set up in the chase or a stereotype taken 11

therefrom as either will register with the intagliographic plate for the one has emanated from the other. First print with the intagliographic plate by which the ground around the letters, characters or figures is colored, and then print the shades of another color with the original form of types or with the stereotype plate taken therefrom. In this way with a proper register the shades can be printed on the ground with perfect accuracy, for the plate which makes the first impression is the exact duplicate of the form of types, without the shading surfaces, so that the intaglio surface of the two will perfectly correspond.

For the production of poly-chromatic printing plates for printing letters, as shown at Fig. 11. For this purpose take an intagliographic plate produced according to the first part of my invention and surround it by a border into which run wax, stearin, or other equivalent substance which will melt by a moderate degree of heat, and thus obtain a reverse duplicate which will have the letters or characters in relief. Then surround this cast with a border and pour the solution of plaster thereon and as it begins to harden or set, with a sharp straight edge, scrape off the plaster to a level with the surface of the relief letters or characters and after the plaster is thoroughly set and hard I apply sufficient heat to melt out the wax or stearin and thus obtain a plaster mold for a metallic stencil plate (see Fig. 12) with the letters or characters in open work corresponding with those of the intaglio plate.

If it be desired to produce letters or characters resembling those represented at *j* (Fig. 11), first print with the intagliographic plate, which colors the ground, leaving the letters or characters of the original color of the surface printed upon. Then melt out the wax or stearin from the plaster stencil plate and secure that face of it, which was in contact with the wax against a suitable plate and cast a metal plate therefrom, which will be a duplicate of the intaglio plate, but with the letters or characters in relief, and which, having emanated from it will register perfectly with it, so as to print any desired color on the parts of the paper left untouched by the intaglio plate, and as the plate with the relief letters or characters is a cast taken from a mold made on the wax molded within the intaglio letters or characters, the contraction of the wax and of the metal will make the surface of the relief letters, &c., slightly smaller than the intaglio letters, &c.; hence when printed a line will be left of the original color of the paper between the color of the ground and that last printed within. But if it be desired to produce an effect like that represented by the letter *k*, Fig. 11, I take two casts from the

stencil plate and cut away the center of the letters from one cast, and the top and bottom of the letters from the other, and then produce duplicates of these casts in metal which will, like in the preceding example, 70 register with the intaglio plate, so as to print in any color desired in parts of the surface left untouched by the intaglio plate. In this way the letters or subject may be divided to any extent desired by sub-dividing the stencil plate to any extent so as to produce a series of printing plates each one in succession printing a separate portion and which as they all emanate from the intaglio plate 75 will register most accurately with it.

It is not deemed necessary to describe other varieties as persons acquainted with this branch of the art will be able to modify the arrangements at pleasure.

It will be obvious that after the plaster 80 has been cast around the intaglio or outline types, the surface of the plaster can be further ornamented by cutting lines into its surface which lines will be reproduced by stereotyping. And although I have described the use of plaster of Paris in my 85 process and wax or stearin, I do not wish to be understood as limiting myself to the use of these substances as other equivalent substances may be substituted but I mention these because I have tried them with 90 success and believe them to be the best.

What I claim as my invention and desire to secure by Letters Patent is—1. The 100 method of producing intagliographic printing and other plates from forms of types by surrounding the types while in contact with a glass plate or its equivalent, with plaster of Paris or some equivalent therefor so that when set, the surface of the plaster will be on the same plane with the surface of the types, and then stereotyping the 105 form of types thus surrounded substantially as and for the purpose specified.

2. I also claim the method of producing 110 embossing plates by taking a cast, in plaster or its equivalent, from an intagliographic plate and then stereotyping such plaster cast substantially as specified, thus producing a reverse duplicate in relief, as set forth.

3. I also claim the method of producing 115 what are called illuminated printing plates for printing shaded intagliographic letters, characters or figures by producing an intagliographic plate in accordance with the first part of my invention from a form of shaded types, and then removing the plaster from the form of types substantially as described, so that after printing in intaglio with the intagliographic plate the shadows 120 can be printed either with the form of types, after the plaster has been removed or with a stereotype taken therefrom as set forth.

4. And finally I claim producing poly-chromatic printing plates from an intaglio- 130

graphic plate by taking a cast therefrom in relief substantially as described, and from such relief obtaining what I term a stencil plate or plates from which the plate or plates is or are obtained, to have the letters, characters, or figures in whole or in part in duplicate of the intagliographic letters, &c., and in relief, substantially as described so as to register therewith, as described.

JOHN DONLEVY.
